EARTH ANCHOR

Albert B. Chance, Centralia, Mo.

Application June 23, 1930. Serial No. 462,954

4 Claims. (Cl. 189—91)

The present invention relates to earth anchors, and is particularly concerned with anchors of the screw type, adapted to be driven into the ground by the rotation of the anchor.

5 The screw anchors of the prior art are generally provided with a centrally located body or hub, which must be of sufficient size and strength to provide an adequate support for the inclined screw flange and to provide a connection between the anchor and a guy rod. The central body or hub of a screw anchor presents considerable resistance to the installation of the anchor, since the surrounding earth must be compressed sufficiently to make space for the hub, 10 and the work of compressing and compacting the earth to make room for the anchors of the prior art is accomplished entirely by the rotation of the anchor by means of a wrench. The labor of forcing such anchors into the ground, therefore, 15 depends upon the character of the soil, but is generally quite arduous.

One of the objects of the present invention is the provision of an improved method of installation of screw anchors, by means of which the resistance to the installation of such anchors is materially reduced, the labor is decreased, and the anchors may be installed in harder or more difficult soils.

Another object is the provision of an improved 30 earth anchor assembly which may be installed with less physical effort than the devices of the prior art, and which includes one form of apparatus for carrying out the improved method.

Another object is the provision of an improved 35 screw anchor which can be installed more quickly than the devices of the prior art, and with less probability of breaking the anchor when installed under particularly difficult conditions.

Another object is the provision of an improved 40 guy rod which is also adapted to serve as a guide and wrench for the installation of a screw anchor.

Another object is the provision of an improved 45 method of installation of screw anchors including the formation of a preliminary pilot hole for receiving and guiding the hub of the screw anchor during the screwing operation.

Another object is the provision of an improved 50 method of installation of earth anchors which can be carried out by several different forms of apparatus.

Another object is the provision of an improved 55 earth anchor of the screw type, the guy rod of which is adapted to be embedded in the earth by merely driving down the rod when it is desired to abandon the anchor and rod.

Other objects and advantages of the invention will be apparent from the following description and from the accompanying drawings, in which similar characters of reference indicate similar parts throughout the several views. 60

Referring to the drawings, of which there are two sheets;

Fig. 1 is an elevational view of an anchor installation constructed according to the present invention, with the parts in the position which 65 they assume when the anchor has been driven into the ground for a short distance.

Fig. 2 is a medial sectional view taken on a vertical plane through the anchor and eye of the 70 guy rod.

Fig. 3 is a plan view of the anchor.

Fig. 4 is a view similar to Fig. 1, of a modified form of anchor.

Fig. 5 is a view similar to Fig. 2, of the modified 75 construction.

Fig. 6 is a plan view of the modified anchor.

Referring to Figs. 1 to 3, the earth anchor which is indicated in its entirety by the numeral 10, preferably consists of an integral metal member formed by a casting operation and having a central body portion or hub 11 which is adapted to provide a support for one or more screw flanges 12 which project laterally from the hub 11 and extend spirally about the hub. The screw flanges 12 may take any of the conventional forms which 85 are adapted to draw the anchor into the earth to install the anchor, and which are also adapted to provide an increased bearing surface for the anchor after the anchor has been installed.

The body or hub 11 may be of any shape, but is 90 preferably substantially cylindrical in form to decrease the resistance to the rotation of the anchor in the earth, and the hub 11 may be provided with a tapered lower portion 13 if the head 14 of guy rod 15 is of smaller size than the body 95 11 of the anchor.

In some embodiments of the invention, such as that illustrated in Figs. 4 to 6, the head 18 of guy rod 17 is adapted to form a pilot hole of sufficient size to receive the body portion 11 of 100 the anchor 10, and consequently the body portion 11 need not be provided with a tapered lower end.

The guy rod 15 preferably comprises a steel rod 105 which is provided with a lower head 14 having a point 18 adapted to cam aside the earth to form a pilot opening when the rod 15 is driven into the earth.

In the embodiment of Figs. 1 to 3, the guy rod 110 15 is circular in cross section and the body 11

of anchor 10 is provided with a circular bore 16 to slidably receive guy rod 15. The lower end of body 11 is also provided with a socket formation 19 for receiving head 14.

5 The upper end of guy rod 15 may be provided with threads 20 adapted to receive the body 21 of an eye structure having a threaded bore 22 and an eye 23 formed in the body. The eye 23 may consist of two upwardly projecting flanges 24, 25, 10 joined by a yoke 26 having an inner surface 27 of substantially the shape of a horseshoe and the eye 23 is provided with a curved groove 28 extending through the eye about the yoke 26 for receiving and supporting the cable which is attached to 15 guy rod 15.

Anchor 10 may be provided with a socket 29, of the same shape as that disclosed in my prior application, Serial No. 228,463, filed October 24, 1927, on Screw anchors, or with any type of non-circular socket. When the anchor is provided with a 20 cruciform socket, an adapter 30 is used having a lower cruciform portion to be received in the socket 29 and an upper square portion 31 to be received in a square tubular shaft 32. The tubular shaft 32 is preferably of considerably less 25 length than the guy rod 15, in order to provide sufficient clearance, so that the guy rod may be driven in preliminary to the installation of the anchor to form a pilot hole, and the tubular shaft 30 32 may be provided with a wrench consisting of a body 33 having a transverse socket 34 of form 35 complementary to the shaft 32 and having a pair of outwardly projecting handles 35. If desired, the wrench may be of the exact type illustrated in said prior application.

Referring to Figs. 4 to 6, the earth anchor assembly of this embodiment differs from that of Figs. 1 to 3 in that the hub 11 of the anchor has been provided with a non-circular or square aperture 36 instead of the bore 16, and the guy rod 17 has been made complementary in cross section, as for example, square in the anchor illustrated. Thus the anchor 10 of this modified device is slidably but non-rotatably, mounted 40 upon the guy rod 17, and the guy rod 17 may be used as a shaft for engagement with the wrench body 33 in the installation of the anchor, eliminating the tubular shaft 32 of the previous embodiment. The wrench may be similar 45 in form but is provided with a smaller socket or non-circular aperture 37 adapted to slidably but non-rotatably receive the non-circular guy rod 17.

In this embodiment, the guy rod 17 has been 50 provided with a pointed head 38 having a substantially frusto-conical point 39 increasing in width toward its upper edge 40 to substantially the same size as the cylindrical hub 11 of the anchor. The heads 14 or 38 may in either case 55 be formed by upsetting the end of the guy rod, or the guy rod may be provided with a threaded bore 41 and the head with a threaded, axially located stud 42 to be received in the bore 41, to secure the head on the guy rod. The upper 60 end of guy rod 17 may be substantially the same as that of guy rod 15.

The improved method of installation is described as follows:

In order to decrease the resistance encountered 70 in the installation of the screw anchor, I have found that it is highly desirable to form a pilot hole 43 as a preliminary step to the installation of the anchor.

The pilot hole 43 should preferably extend in 75 substantially the same direction in which it is de-

sired to install the guy rod, and consequently the pilot hole should preferably be formed by holding the guy rod with its point resting on the ground and in line with the proposed direction of extension of the guy or cable. The guy rod may then be driven into the earth in such position to form a pilot hole and the pilot hole 43 is preferably of sufficient size to receive the hub 11 of the screw anchor. The present invention includes both the formation of pilot holes by the rod or other tool separate from the anchor or in conjunction with the anchor as illustrated by the present apparatus.

80 In the practice of the method under some conditions, the guy rod might be withdrawn in whole or in part, as for instance by leaving the head 18 embedded in the ground, after which the screw anchor 10 may be installed in the usual manner by means of a shaft and wrench, and the body 11 will naturally follow the pilot hole 43 to the desired location. The amount of resistance to the installation of the anchor will be very materially reduced, since the anchor need not perform the function of compressing the earth sufficiently to make room for the hub 100 11 and the direct or "head-on" resistance to the passage of the screw anchor has been substantially eliminated.

85 Other modes of the practice of the foregoing improved method may be carried out by means of the apparatus disclosed in the foregoing description, and the device illustrated in Figs. 1 to 3 may be installed as follows.

90 The anchor having been assembled with a shaft and wrench, as shown in Fig. 1, and held in the same position previously described, the guy rod 15 may be driven into the earth by means of a sledge or other tool applied to the eye structure 21, and during the driving operation the guy rod 15 will slide through the anchor 10 forming the pilot hole 43. The guy rod is purposely made longer than the tubular wrench shaft 32, in order to permit the preliminary driving of the guy rod, during which the pilot hole is formed.

95 After this, the screw anchor 10 may be rotated in the usual manner by means of the shaft 32 and wrench 33, during which operation the screw anchor will progress along the guy rod 15, sliding and rotating upon the guy rod 15 and also following the pilot hole 43.

100 In the embodiment of Fig. 1, it will be observed that the head 14 of the guy rod is slightly smaller than the hub 11 of the anchor, and consequently the pilot hole 43 need not in every case be fully as large as the hub of the anchor. In any 105 case, however, the formation of the preliminary pilot hole and/or the preliminary location of the guy rod in place to guide the anchor, greatly decreases the amount of labor necessary to install the anchor and the anchor may be installed in 110 a shorter time with less physical effort.

115 In the embodiment of Fig. 4, the guy rod 17 is driven in the same manner to form the pilot hole 43, after which the guy rod 17, point 16 and anchor 10 may all be rotated by means of wrench 33 to screw the anchor 10 into place. During 120 this operation the anchor 10 slidably, but non-rotatably, engages guy rod 17 and progresses down the guy rod until it strikes head 16, after which the anchor may be driven still further in the 125 usual manner, if desired, or several driving and securing operations may be used.

130 It should also be noted that in either case, after the anchor has been installed, the guy rod may be abandoned and concealed by simply driving 135

upon the eye structure 21 until the guy rod 15 or 17 is completely embedded in the earth. During this operation the guy rod will slide through the anchor and the anchor is, of course, also 5 abandoned.

It will thus be observed that I have invented an improved method of installation of earth anchors of the screw type, which may be practiced by several different forms of apparatus.

10 The improved method, including the formation of the pilot hole, materially decreases the amount of resistance to the installation of the screw anchor and enables the installation of anchors in harder ground, where their installation would 15 otherwise be impossible. The improved anchors may also be installed with less physical effort and in a shorter period of time, and the present anchor may be very economically manufactured.

While I have illustrated a preferred embodiment of my invention, many modifications may be made without departing from the spirit of the invention, and I do not wish to be limited to the precise details of construction set forth, but desire to avail myself of all changes within the scope of 25 the appended claims.

Having thus described my invention, what I claim is new and desire to secure by Letters Patent of the United States, is:

1. In an earth anchor, the combination of an 30 earth anchor, having a body portion with a screw flange carried thereby, a non-circular guy rod adapted to be received in a complementary portion for screwing said anchor into place, and said rod passing through said body, whereby said 35 anchor slidably engages said rod as the anchor is screwed into the earth.

2. In an earth anchor, the combination of an 40 earth anchor, having a body portion with a screw flange carried thereby, a guy rod adapted to be received in a complementary socket in said anchor for screwing said anchor into place, and said rod passing through said body portion, whereby said

anchor slidably engages said rod as the anchor is screwed into the earth, and a head formed on said rod below said anchor to form a pilot hole for the body of said anchor.

3. In an earth anchor for guy wires, the combination of an anchor member of the screw type having a substantially cylindrical core with a helically extending flange carried by said core and adapted to provide an enlarged surface for anchoring guy wires and the like, said cylindrical core being provided with an axially extending non-circular aperture, a guy rod slidably mounted in said core aperture and having a cross section complimentary to the cross sectional shape of said aperture, said guy rod having a point at its lower end and an eye at its upper end and a handle carried by said guy rod whereby said guy rod may be driven into the earth by impact on its end and rotated by said handle to cause said screw anchor to progress along said guy rod into the earth along a path predetermined by said guy rod. 80
